CLAIM

We claim the ornamental design for a golf club head, as shown and described.

DESCRIPTION

FIG. 1 is a perspective view of a putter golf club head, as viewed from the bottom and one side.

FIG. 2 is a front plan view of the golf club head of FIG. 1.

FIG. 3 is a rear plan view of the golf club head of FIG. 1.

FIG. 4 is a side elevation view of a toe side of the golf club head of FIG. 1.

FIG. 5 is a side elevation view of a heel side of the golf club head of FIG. 1.

FIG. 6 is a top plan view of the golf club head of FIG. 1.

FIG. 7 is a bottom plan view of the golf club head of FIG. 1; and,

FIG. 8 is a rear cross section view of the golf club head of FIG. 1, taken along line 8-8 of FIG. 7.

The dashed lines in the drawings are for purposes of illustrating environmental structure as well as portions of the design that form no part of the present claimed design.
